UNITED STATES PATENT OFFICE.

LINDSAY R. HURST, OF LOUISVILLE, KENTUCKY.

LAUNDRY APPARATUS.

Application filed July 21, 1920. Serial No. 397,907.

To all whom it may concern:

Be it known that I, LINDSAY R. HURST, a citizen of the United States, residing in Louisville, in the county of Jefferson and State of Kentucky, have invented certain new and useful Improvements in Laundry Apparatus; and I do hereby declare the following to be a full, clear, and exact description of the invention, such as will enable others skilled in the art to which it appertains to make and use the same.

My invention relates to laundry apparatus especially of the type designed for domestic use, and the primary object of the invention is to provide an apparatus having all the essentials of a laundry outfit compactly arranged so as to be contained in a single cabinet when not in use, and so disposed relative to each other when opened up that the user may effect soaking of the clothes, wringing, washing, rinsing and starching and bluing, ironing and airing after ironing within a minimum space, the cabinet as a whole being designed to occupy but a small amount of space.

A further object of my invention is to provide a simple and highly efficient washing machine composed of but few parts which are not easily disarranged and which insure ready manipulation by those not skilled in mechanics, and one which provides for a maximum impact of the water against the soiled clothes with but a minimum of action of the movable clothes container, thus insuring a quick and thorough cleansing of the articles to be washed, all the mechanism of the washer being confined within the cabinet so that there is no danger whatever of personal injury or injury to the clothing of the operator by catching in any of the gearing, the machine being readily started and stopped by the simple turning of a switch member conveniently placed on the outside of the cabinet, the mechanism, however, being readily accessible through appropriate closures in the cabinet when necessary for repairing.

In the drawings, Figure 1 is an elevation of my improved laundry apparatus, parts being in section and others broken away. Figure 2 is a view at right angles to Figure 1, the cabinet being in section and the water

receptacle being broken away to show the clothes container.

In the drawings, 1 designates a cabinet, 55 which may be made of wood or of metal, suitably braced and provided with supporting casters 2. The cabinet forms a housing for the washing machine and its operating mechanism, including the motor, for the wringer, and for the ironing board with its adjuncts, each of which parts of the laundry apparatus will be hereinafter fully described. At its top the cabinet is provided with a hinged cover. The cover has two 60 sections, 3, 3^b, hinged together, the smaller section, 3, being adapted to lie flat against the outside of the cabinet when the cover is opened up and used as a table, it being supported in this open position by chains 4. 65 The motor mechanism and the drain pipe from the water receptacle may be reached through openings in the side or sides of the cabinet, suitable closures, such as 5, covering these openings, it being one of the objects 70 of my invention that every part of the apparatus is enclosed within a sightly cabinet 75 when the apparatus is not in use.

The washing machine.

Appropriately supported within the cabinet is a metallic water receptacle 10 with a valved drain 12 which extends to the side of the cabinet, access to this drain being had through one of the closures 5 in the side of 85 the cabinet. The clothes container 13 is preferably of oval shape in side elevation and is formed of corrugated copper, although other materials may be used for this purpose. The corrugations are arranged 90 transversely throughout the greater portion of the ends and the bottom of the container and the major number of the corrugations, which includes the bottom and part way up each end, has a series of slits 14 in the wells 95 of the corrugations, these slits being of approximately one-sixteenth inch in width. Adjacent the opening 15 of the container and part way down each end the wells of the corrugations have slits 16 of greater 100 width than the slits 14. The larger slits permit quick passage of the water at the points where the greatest pressure is applied. The sides 17—18 of the container are

secured to the corrugated metal body portion by having the sides of an exact size with the outermost plane of the body. Midway the two ends and extending down the 5 sides and across the bottom of the body of the container is a groove 19 which forms a seat for a U-shaped saddle or hanger 20 by which the container is suspended within the water receptacle, outwardly extending trunnions 21 and 22 of the saddle being pivotally supported in bearings 23, 24, the former being secured to one of the sides of the cabinet and the latter to a cross piece 25 within the cabinet, the packing of these bearings 10 being arranged in boxes outside of the water receptacle so that soapy water seeping through the bearings will aid in lubrication. The trunnion 22 is elongated and to it is fixed a segment 26 by which the container 15 is rocked on its bearings through a complementary segment 27 on a stub shaft 28 projecting from the cross piece 25, the segment 27 having an arm 29 connected with an actuating rod 30, the other end of the rod being 20 attached to a crank 31 loose on an extension 32 of a shaft 33 supported by bearing blocks 34, the shaft being driven by a gear 35 in mesh with a worm 36 on the shaft 37 of motor 38. The crank 31 is weighted, as 25 at 39, to counterbalance the weight of the members connected therewith to effect centering of the saddle when the apparatus is brought to a standstill. A clutch 40 effects the interlocking of the crank with the driven shaft 33, the clutch being thrown into and 30 out of engagement by bell crank leverage 41 which is operated by a handle 42 projecting outside the cabinet 1, the lever mechanism being held in either of its two positions by a spring 43 which in whatever position the lever parts may occupy is at one side of the 35 axis of the handle.

The clothes container is fastened to the saddle 20 by spring clips 44 which are also 40 effective for securing the cover 45 to the container. After the washing operation is completed the container as a whole may be lifted from its saddle by simply disengaging the clips 44. To insure an oscillating 45 action of the container the trunnions 21 and 22 are at a point on the saddle which is above the horizontal center line of the container.

As before stated, the container is of oval 50 shape in side elevation. It is preferably so placed within the water receptacle that its ends leave but little clearance between themselves and the end walls of the receptacle, greater space existing between the bottom 55 of the container and the bottom of the receptacle. This formation insures the displacement of the water from the bottom of the receptacle and its impinging with greater force against the upper portion of 60 the ends of the container at which point the

wide slits 16 are provided so that the water will be freely passed into the container and with a force which will act quickly on the articles contained therein.

In operating the washing machine, the receptacle is first filled to the desired depth with water, the valve in the drain being closed. Clothes to be cleansed may then be inserted in the clothes container and the latter hung in its saddle, or the clothes may 70 be put in the container after the latter has been suspended in position. With the cover applied to the container and fastened by the spring clips 44 it is now only necessary to turn the handle 42 so as to throw the operating gears into mesh with the motor through the clutch 40, the motor having been previously started, or the clutch may 75 be first operated and the motor then energized. The parts are geared to a ratio of 80 about 48 to 1 so as to economize by avoiding the necessity of providing high speed bearings. The reciprocating action of the suspended container is sufficiently fast through this ratio to insure the best results. 85 To prevent splashing of the water and at the same time insure retention of the heat a cover is fitted over the water receptacle. The rocking and oscillating motions are imparted to the container by the gearing 26, 90 27, through the crank connections with the motor. The washing operation may be stopped either by cutting off the current to the motor or by disengaging the clutch members. 95

I claim as my invention:

1. Laundry apparatus including a housing, a washing machine within said housing comprising a water receptacle, a clothes container, a saddle mounted for swinging action within said receptacle, said saddle supporting said clothes container, spring clips carried by said saddle for fastening the container thereto and simultaneously binding the cover to said container, a gear set for swinging said saddle and clothes container, and motive power connections for actuating said gear set. 105

2. Laundry apparatus including a housing, a washing machine within said housing comprising a water receptacle, a clothes container having a recess extending down its sides and across its bottom, a U-shaped saddle mounted for swinging action within said receptacle, said saddle supporting said 110 clothes container by engagement with the recessed portion of the latter, spring clips carried by said saddle for fastening the container thereto and simultaneously binding the cover to said container, a gear set for 115 actuating said saddle and clothes container, and motive power connections for driving said gear set. 120

3. Laundry apparatus including a housing, a washing machine within said housing 125

comprising a water receptacle having oppositely arranged bearings, a U-shaped saddle having trunnions journaled in said bearings, a clothes container having a recess extending down its sides and across its bottom to receive said saddle when the container is placed in said receptacle, a gear fast on one

of the trunnions of said saddle, and motive power connections for oscillating said gear to effect swinging of said saddle and clothes container. 10

In testimony whereof I have signed this specification.

LINDSAY R. HURST.
